cago, Ill., a corporation of Illinois

Application March 9, 1937, Serial No. 129,871

3 Claims. (Cl. 204—9)

This invention relates to the production of bromates.

It is the principal object of the invention to provide a simple, economical, and commercially desirable process for the production of bromates such as potassium bromate and other alkali metal bromates.

It is a further object to provide a highly satisfactory electrolytic process for the production of bromates in which the bromate is secured in a continuous manner and under controlled and uniform conditions.

It is a still further object to provide such a process for the production of bromates utilizing a depolarizer such as a chromate, in which the bromate is obtained in a uniform and highly pure condition, and substantially free of undesirable color resulting from the chromate.

Other objects and advantages will be apparent from the description, the accompanying drawing, and the appended claims.

In the drawing,

Fig. 1 is a diagrammatic view or flow sheet representative of the practicing of the present invention;

Figs. 2 and 3 are a top plan and a vertical sectional view respectively of an electrolytic cell which is suitable for use in the practicing of the invention.

In accordance with the present invention there is provided a process for the production of bromates, which provides for the securing of the bromates in a highly pure condition, of uniform characteristics, and substantially free of objectionable color. The process is carried out electrolytically, and in a continuous manner, the conditions of the electrolytic reaction being at all times under definite control to provide for securing a product having the characteristics desired. The process is highly economical in its utilization of materials and electric current, and provides for the ready removal and recovery of a substantially pure bromate product in a simple and easy manner, avoiding the difficulties in recovery of the product which result in the carrying out of a batch process.

Referring to Fig. 1 of the drawing which discloses a typical flow sheet with apparatus suitable for carrying out the invention being illustrated diagrammatically thereon, there is shown at 10 a feed box through which the solution is supplied to the electrolytic cell, indicated diagrammatically at 11. The solution or feed liquor as supplied to the cell is a solution of the bromide from which it is desired to form a corresponding

bromate. While not so restricted, the invention has been developed more particularly for the production of potassium bromate, and the following description will be presented using potassium as an example of an alkali metal bromate produced through the practicing of the invention.

This feed liquor is preferably supplied in a solution of controlled concentration such for example as approximately a 25% solution of potassium bromide. Suitable results are secured using a lower concentration, as it is found that in the continuous process of this invention lower concentrations, for example down to 5.0%, or even lower, produce entirely satisfactory results in operation and the maintenance of the higher concentration ranges which are important in the operation of a batch process are not found to be necessary in the carrying out of the present invention. The feed liquor also preferably contains in solution a depolarizing agent, preferably an alkali metal chromate corresponding to the bromate which is produced. For example a solution containing .5 gram of potassium chromate per liter as a depolarizer has been used with satisfactory results. A substantially uniform concentration condition in the feed liquor supplied to the cell is preferably maintained by the controlled addition of the bromide solution with such addition of the chromate as required, to bring the concentration of the bromide up to the desired range.

The temperature at which the feed liquor enters the electrolytic cell is important in connection with the solution temperatures maintained throughout the entire continuous cycle, in order that through the use of a controlled temperature condition at all points in the cycle proper solubility characteristics will be maintained, in order to secure precipitation of constituents in certain phases of the process and to avoid such precipitation where not desired. Ordinarily it is preferred that the temperature of the entering feed liquor be substantially that of room temperature or slightly below room temperature.

The electrolytic cell may have a widely varying structure although it is preferably constructed of suitable non-reactive material, and arranged to provide adequate interchange and mixture of the liquor flowing through the cell, as by the provision of suitable baffles or the like. In Figs. 2 and 3 is shown a suitable construction of cell for use in this invention, and reference

is made thereto as showing a preferred embodiment of cell structure for this purpose.

The cell is generally rectangular in shape, and of elongated form, the side walls 15 and base 16 being formed of clear, close-grained hard wood having an overlying coating of Bakelite or varnish baked on the surface thereof, to provide an inert surface in contact with the liquor. A series of anode members 17 are electrically connected with a positive bus bar 18 by suitable connectors 19, the bus bar extending along one side of the cell, and providing electrical connection and support for the spaced series of anode plates. Preferably these plates are formed of graphite although other suitable materials may also be used. Alternate plates are recessed into the base 16, as shown at 20, such plates terminating below the top of the cell, to leave a passage 21 thereabove, the other group of plates alternating therewith being supported above the bottom of the cell to leave a lower passageway 22. This alternating relation of the anodes thus effects the baffling of the liquor, requiring it to successively flow vertically upward and downward through its passage through the cell to thereby secure substantial mechanical reaction of the liquor, resulting in the bringing of the body of liquor in more intimate contact with the series of cathodes.

The cathodes are shown at 24, alternating with each of the anodes 17 and supported from the bus bar 25 by connectors 26, the ends of which are clamped upon the end walls 15 of the cell, by means of clamping structure 26, thereby supporting the bus bar 25 in elevated position along one side of the cell. The cathodes are preferably also formed of graphite, and are of substantially less area than the corresponding anodes; for example in the structure shown, the total area of the cathodes is approximately half the area of the anodes. The cathodes are positioned substantially centrally located of the cell, and extend into contact with the base thereof, thereby requiring the liquid flow to traverse the cathode transversely of the cell. The cathode thus provides an additional baffling action, requiring passage of the liquor in a direction substantially transverse to the baffling action afforded by the anodes, the combined electrodes thereby securing a highly effective baffling action, resulting in bringing the entire body of feed liquor quickly and substantially uniformly into reactive contact with both sets of electrodes.

At the discharge end of the cell there are provided a pair of discharge openings 27 through the base 16, the openings being provided with a glass tube 28, extending therethrough, to permit of constant and regulated discharge of the liquor from the cell. It will be understood that various types of cells may be used, and that the present description sets forth a construction of cell which has been found to give suitable and satisfactory results. Further, other materials may be used for the electrodes if desired, and auxiliary baffling means in addition to or in place of the electrodes themselves may be used if desired.

In the electrolytic operation the passage of the current through the solution of potassium bromide results in potassium going to the cathode and being plated out as a metal thereon, the bromine going to the anode. However as soon as the potassium is formed as such it immediately reacts with the water to form potassium hydroxide with the evolution of hydrogen as a gas at the cathode. The potassium hydroxide then reacts with the bromine formed at the anode with

the production of potassium hypobromite and potassium bromide. The potassium hypobromite by a self-oxidation process which takes place under suitably controlled conditions converts itself into potassium bromate in accordance with the following equations, showing the total quantities of reactive ingredients required.

It is highly important in the carrying out of these reactions to secure the bromate, that the proper conditions are maintained and controlled within the cell. Thus it is important that the temperature of the cell be controlled, and preferably maintained below the boiling point of bromine which is of the order of 60° C. If the temperature rises above this point, the bromine tends to pass out of solution, and is lost from the process. This is undesirable not only because of the loss of the bromine itself, but because such loss results in the unbalancing of the reaction, certain of the potassium hydroxide being unable to react with bromine, and thereby building up and increasing the alkalinity of the liquor. Increase in alkalinity of the liquor tends to result in stabilization of the hypobromite, thereby retarding the self-oxidation process and tending to prevent the conversion of the hypobromite into bromate. This control of alkalinity is also believed to have an important effect upon the subsequent processing and color condition in the bromate crystals as will be discussed more in detail hereafter.

In the batch operation it was ordinarily necessary to operate the cell under a higher alkalinity condition in order to secure the desired diffusion and interaction as between the potassium hydroxide and the bromine. But in the practicing of the invention of this application a lower concentration of potassium hydroxide and bromine are preferably used, with entirely satisfactory results because of the mechanical intermixture action taking place in this cell as a result of the passage of liquor therethrough.

Thus during its passage through the cell the liquor is continually brought into intimate contact with both anode and cathode surfaces, so that the products of the electrolysis are brought into intimate reactive contact with each other even when present at low concentrations. This is highly desirable since it provides for securing proper results without entailing the difficulties resulting from higher concentrations of bromine and of caustic. While it is difficult to secure actual pH value measurements because of the strongly oxidizing character of the solutions, in actual operations on a plant scale it has been found that where the solution from the batch cell is strongly alkaline to litmus, that from the continuous cell of this invention is not strongly alkaline.

It is also believed that the proper control of the pH condition during the electrolytic operation has an important effect in regard to the color of the bromate as produced. The color may be imparted to the bromate originally by the chromate used as a depolarizer, usually resulting in coloring the bromate in the same manner as a solution of the chromate itself. When the bromate is formed in the batch process, with a higher alkalinity condition, it seems that the chromate is incorporated into the bromate crystals

or cake as formed, the combination apparently being some complex molecular or physical inter-relationship which makes it highly difficult to separate the chromate from the bromate. In certain cases where bromate crystals have been produced under such high alkalinity conditions and have an objectionable color, it is found that even though such crystals are dissolved and recrystallized a number of times the color still remains, 10 gradually fading out with such successive crystallizing operation. The Hochwalt and Waluszsz Patent 1,919,721, assigned to the same assignee as the present invention, discloses certain inventions providing for the production of a decolorized bromate product from the batch process.

In accordance with the present invention however the bromate as initially produced, under the controlled conditions described, is substantially free of color, the chromate apparently not being attached or incorporated with the bromate in the same manner as occurs in the batch process. The suspension of the bromate crystals may have a colored appearance because of the presence of the chromate in solution in the liquid; however this colored solution can be readily washed out, substantially completely freeing the bromate crystals of undesired color without the necessity of dissolving and recrystallizing the bromate itself. And it is believed that this production of the bromate crystals in a different form, and substantially free of color, arises as a result of the predetermined controlled pH value conditions existing during formation of the bromate in the electrolytic cell.

35 A preferred temperature condition for the operation of the cell has been found to be of the order of 45° C. to about 50° C. As explained above, higher temperatures tend to result in undesirable loss of bromine, and at temperatures materially below this range the resistance of the cell is found to increase somewhat, resulting in lower operating efficiencies. Also it is important to provide for inhibiting the reducing action of the hydrogen as produced at the cathode, the hydrogen having a tendency if not removed to reduce the hypobromite. For this reason it is preferred to make the area of the cathodes substantially less than the area of the anodes to thereby increase the tendency of the hydrogen to bubble up through the liquid and escape as a gas. Heat also tends to assist in this escape of the hydrogen and accordingly it is preferred to operate the cell generally within the temperature range indicated above. The action of the depolarizer facilitates the escape of the hydrogen and also appears to function in the nature of a catalyst, tending to prevent an objectionable reduction action taking place at the cathode.

60 The rate of flow through the cell is preferably regulated to produce the desired outlet temperature in the liquor. In an experimental operation, the rate of flow was 8 gallons per minute, with a current of 1000 amperes. The current density may be higher in the present process than in a batch process because as already explained it is not necessary to rely upon diffusion of the products of electrolysis, such diffusion action being greatly augmented by the mechanical movement of the liquor. And it has been found entirely practicable to use higher current densities, while maintaining good current efficiencies. As the current density increases the overvoltage also increases, and there is therefore a practical upper limit which should

not be exceeded for economical reasons. The reduction in the relative size of the cathode tends to increase the cathode drop or overvoltage, and thus while a much smaller cathode area facilitates the depolarizing action of the cell, it is not advisable that the cathode be so small as to result in excessive overvoltage. As above indicated, the preferred ratio of cathode to anode area for practical commercial operations has been found to be approximately 1 to 2.

10 Satisfactory results have been secured with current densities of the order of 7 amperes per square decimeter of anode surface with a voltage of about 5 volts. The voltage is increased with higher current densities, for example at a current density of 10 amperes per square decimeter a voltage of about 7½ volts is desired, and at a current density of 20 amperes per square decimeter, the voltage desired is about 12 volts.

15 As will be apparent from the reaction equations set forth above, the reactions taking place in the electrolytic cell result in the production of a relatively small amount of potassium bromate and a much larger amount of potassium bromide, these quantities being approximately five times the molecular weight of potassium bromide to that of potassium bromate. The bromate however is much less soluble in the solution than bromide. For instance at 20° C. a saturated solution of bromate in water contains approximately 6½% potassium bromate, while a saturated solution of potassium bromide at the same temperature contains about 50%. At 20° C. a saturated solution of potassium bromate contains approximately 14.9% bromate. The temperature of the liquor as it leaves the cell, as already stated, is preferably controlled to be of the order of 45° to 50° C. And at that temperature the solution is far from being saturated either with the bromide or the bromate, so that both salts will readily remain in solution.

25 As the treated liquor issues from the discharge openings in the cell, it first passes through a filter indicated generally at 30, which may be of any desired type, for the purpose of filtering out any insoluble foreign particles which are suspended in the liquid, such for example as small particles of graphite which have a tendency to flake off from the electrodes. The filtered liquor, freed of suspended particles, then passes to a sump 31, and is pumped by suitable pumping means 32 into the cooling and precipitating tank 33. This tank is provided with a water jacket or similar means to effect reduction in the temperature of the liquor, and is further preferably provided with an agitating member 34 for maintaining the precipitated particles in suspension in the liquid and avoiding settling at the bottom of the tank.

30 In the tank the liquor is cooled to a suitable temperature to effect the precipitation of bromate from the solution, the bromate precipitating out as crystals which are held in suspension in the liquor and are prevented from settling in a hard cake at the bottom of the tank as a result of the agitation. Agitation also serves to facilitate heat transfer from the liquor to the cooling medium through movement of the hot liquor, and further is effective in keeping the 35 crystals in suspension where they act as seed crystals, thus avoiding undesirable supersaturation. It is desired to so control the temperature condition throughout the process as to require all of the precipitation to take place within this 40

cooling tank. This is accomplished by so regulating the temperature that no further temperature drop takes place in the system following the cooling of the liquor within the tank. For this purpose the liquor may be cooled to room temperature, or preferably to a temperature slightly below room temperature so that any subsequent change of temperature in the liquor will be an increase in temperature rather than a drop in temperature.

The bromate content of the liquor as it is supplied to the cooling tank is such that the saturation point of the liquor for the bromate will be reached before the temperature is cooled to the room temperature condition as described, thereby resulting in the precipitation of bromate from the solution. Even though there is a larger molecular weight of bromide present, because of the much greater solubility of the bromide, its saturation point is not reached even at such lowered temperature condition, and no bromide is precipitated out. Thus there results a highly effective and quite pure separation of bromate, free of bromide, with all of the bromide remaining in solution for subsequent reuse in the cyclic process.

In the batch process the bromate was usually precipitated out in the bottom of the cell, in the form of a hard cake, which was difficult to take out of the cell, requiring a separate removal operation of considerable difficulty. In accordance with the present invention, and through the use and maintenance of controlled temperature and solubility conditions throughout the process, the precipitation of the bromate takes place in a suspended condition, so that it is subject to being recovered from suspension as finely divided particles or crystals, in a much easier form than the hard cake produced in the prior art method. Following the precipitation, the suspension is run into a settling tank 35 where the salt is allowed to settle in the bottom of the tank, being drawn off as a sludge from time to time. This precipitated sludge is first washed with clear water, to free the crystals of remaining liquor, the wash water containing certain of the bromides in solution being returned to the system as make-up water so that complete recovery of the bromides, and any dissolved bromate, is secured. The washed bromate crystals may then be subjected to the action of a centrifuge to dry the separated salt which is then available for use as such.

The supernatent liquor is flowed over the tank 35 after the settling operation and is returned to the feed box 16 to be used subsequently in the process. Preferably the make-up ingredients which comprise fresh water and potassium bromide, are also added at the feed box. For example the required amount of bromide in order to maintain a desired concentration of bromide in the liquor may be added from time to time in solution form to the feed box, the wash water from the centrifuge with additional water if necessary being used for disclosing the bromide; or the bromide may be placed in solid form beneath the inlet to the feed box so that the liquor flowing into the feed box will dissolve the fresh salt and carry it into the cell in solution for subsequent use. All of the tanks and cells are preferably operated in the full condition as by means of an overflow so that one level gage, preferably positioned on the settling tank, will accurately measure the total liquid in the system. By reference to such gage and by measurement

from time to time of the concentration of the bromide in the liquor, the necessary addition of water and fresh bromide may be made to secure and maintain the desired concentration conditions.

Thus the present invention provides a highly satisfactory process for the production of bromates, providing for economical and efficient production with a minimum loss of reactive constituents, and a minimum requirement in quantity of electrical energy. Through the proper maintenance and control of desired temperature and pH value conditions, unnecessary loss of bromine is avoided, and the building up of high alkalinities in the electrolytic cell, with the attendant objectionable results thereupon, are effectively avoided. The invention further provides for the production of bromates which are substantially free of color, and do not require separate processing to purify and decolorize the product. And further the bromate as produced is substantially free of bromides and is obtained in desired crystals in finely divided form greatly facilitating the recovery of the product from the system.

While the process herein described constitutes a preferred embodiment of the invention, it is to be understood that the invention is not limited to this precise process, and that changes may be made therein without departing from the scope of the invention which is defined in the appended claims.

What is claimed is:

1. A continuous electrolytic process for the production of alkali metal bromates from an aqueous solution containing the alkali metal bromide and an alkali metal chromate as a depolarizer with the production of the alkali metal bromate in a condition substantially free of discoloration resulting from such chromate which comprises flowing continuously through an electrolytic cell containing a plurality of spaced anode and cathode electrodes a stream of said bromide solution, passing an electric current through the cell to cause continuous formation of reactive bromine at the anodes and the alkali metal hydroxide at the cathodes, simultaneously diffusing the formed bromine and hydroxide in substantially the quantities as formed into the solution in its passage through the cell by causing movement of substantially the entire body of the liquid within the cell into intimate and absorbing contact with the successive anodes and cathodes at a rate controlled to absorb and remove from each electrode the entire quantity of materials formed thereon and to diffuse the materials from the several electrodes into and through the solution into intimate reactive contact with each other to form hypobromite and resulting bromate in solution with concomitant temperature rise of the solution, controlling the temperature of the solution so that it reaches a maximum value during its passage through the cell which provides for maintaining the bromate in solution and limited to be not in excess of that at which the bromine remains in solution phase and available for said reactive contact in substantially originally formed quantity and approximately 45° C. to 50° C. thereby maintaining low alkalinity in the solution and avoiding occlusion of the chromate upon the bromate, and thereafter withdrawing the solution from the cell and cooling the solution to cause precipitation of crystals of bromate substantially clear and free of contamination with occluded chromate in suspension in the liquor.

2. A continuous electrolytic process for the production of alkali metal bromates from an aqueous solution containing the alkali metal bromide and an alkali metal chromate as a depolarizer with the production of the alkali metal bromate in a condition substantially free of discoloration resulting from such chromate which comprises flowing continuously through an electrolytic cell containing a plurality of spaced anode and cathode electrodes of carbon a stream of said bromide solution of a concentration range of approximately 5% to 25%, passing an electric current through the cell to cause continuous formation of reactive bromine at the anodes and the alkali metal hydroxide at the cathodes, simultaneously diffusing the formed bromine and hydroxide in substantially the quantities as formed into the solution in its passage through the cell by causing movement of substantially the entire body of the liquid within the cell into intimate and absorbing contact with the successive anodes and cathodes at a rate controlled to absorb and remove from each electrode the entire quantity of materials formed thereon and to diffuse the materials from the several electrodes into and through the solution into intimate reactive contact with each other to form hypobromite and resulting bromate in solution with concomitant temperature rise of the solution, controlling the temperature of the solution so that it reaches a maximum value during its passage through the cell which provides for maintaining the bromate in solution and limited to be not in excess of that at which the bromine remains in solution phase and available for said reactive contact in substantially originally formed quantity and approximately 45° C. to 50° C. thereby maintaining low alkalinity in the solution and avoiding occlusion of the chromate upon the bromate, and thereafter withdrawing the solution from the cell and cooling the solution to cause precipitation of crystals of bromate substantially clear and free of contamination with occluded chromate in suspension in the liquor.

3. A continuous electrolytic process for the production of alkali metal bromates from an aque-

ous solution containing the alkali metal bromide and an alkali metal chromate as a depolarizer with the production of the alkali metal bromate in a condition substantially free of discoloration resulting from such chromate which comprises flowing continuously through an electrolytic cell containing a plurality of spaced anode and cathode electrodes a stream of said bromide solution of a concentration range of approximately 5% to 25%, passing an electric current through the cell to cause continuous formation of reactive bromine at the anodes and the alkali metal hydroxide at the cathodes, simultaneously diffusing the formed bromine and hydroxide in substantially the quantities as formed into the solution in its passage through the cell by causing movement of substantially the entire body of the liquid within the cell into intimate and absorbing contact with the successive anodes and cathodes at a rate controlled to absorb and remove from each electrode the entire quantity of materials formed thereon and to diffuse the materials from the several electrodes into and through the solution into intimate reactive contact with each other to form hypobromite and resulting bromate in solution at a concentration in excess of approximately 6.5% and less than 14.9%, with concomitant temperature rise of the solution, controlling the temperature of the solution so that it reaches a maximum value during its passage through the cell which provides for maintaining the bromate in solution and limited to be not in excess of that at which the bromine remains in solution phase and available for said reactive contact in substantially originally formed quantity and approximately 45° C. to 50° C. thereby maintaining low alkalinity in the solution and avoiding occlusion of the chromate upon the bromate, and thereafter withdrawing the solution from the cell and cooling the solution to cause precipitation of crystals of bromate substantially clear and free of contamination with occluded chromate in suspension in the liquor.
